UNITED STATES PATENT OFFICE.

ALEXANDER EUSTACE MAGUIRE, OF SILLERY, QUEBEC, CANADA.

ECCLESIASTICAL RITUAL CASE.

1,242,570.

Specification of Letters Patent.

Patented Oct. 9, 1917.

Application filed October 2, 1916. Serial No. 123,260.

To all whom it may concern:

Be it known that I, ALEXANDER E. MAGUIRE, a subject of the King of Great Britain, residing at Sillery, Province of Quebec, 5 Canada, have invented certain new and useful Improvements in Ecclesiastical Ritual Cases; and I do hereby declare that the following is a full, clear, and exact description of the invention, such as will enable others 10 skilled in the art to which it appertains to make and use the same.

The present invention relates to a case or cabinet containing all the requisites for the administration of the last rites in the Roman 15 Catholic Church by a priest in administrating the sacraments to the sick.

An object of the invention is to provide a portable cabinet of this character which when folded will form a compact carrying 20 case containing all of the requisites to perform the ecclesiastical rites of the church in private and when opened will present to view in position all of the contents for administering the last sacraments.

25 With the above and other objects in view which will hereinafter appear as the description continues, the invention consists of the novel features of construction, combination and formation of parts as will be hereinafter more fully described and particularly pointed out in the appended claims.

In the accompanying drawings has been shown the simple and preferred form of the invention, it being, however, understood that 35 no limitation is necessarily made to the precise structural details herein exhibited, but the right is hereby reserved to any changes, alterations or modifications to which recourse may be had that come within the 40 scope of the invention without departing from the spirit thereof or sacrificing the efficiency of the same.

In the accompanying drawings:

Figure 1 is a perspective view of the case 45 when opened;

Fig. 2 is a vertical longitudinal section through the same;

Fig. 3 is a vertical transverse section through the same;

50 Fig. 4 is a vertical section through the case when opened;

Fig. 5 is a detail sectional view through the oil infirmorum section;

55 Fig. 6 is a detail sectional view showing the means for supporting the crucifix;

Fig. 7 is a detail sectional view through one of the candle supporters; and,

Fig. 8 is a sectional view of the holy water bottle.

Referring now more particularly to the accompanying drawings wherein like and corresponding parts are designated by similar reference characters throughout the several views.

The numeral 1 indicates the bottom of the case having its end walls 2 and a front wall 3. The rear wall 4 of the case is a continuation of the bottom 1 but it is hingedly connected thereto along the line 5. Also forming a continuation of the bottom 1 is a top 6 which is hingedly connected to the upper end of the rear wall along the line 7. When the cabinet is folded the latch member 8 carried by the cover 6 is adapted to engage within the lug 9 and secured to the front 75 wall 3 of the cabinet is a handle 10 whereby the cabinet may be easily carried. The interior of the cabinet is to be arranged so as to contain all of the rites or ordinances of a church whereby they may be folded within 80 the cabinet when not in use, but when the cabinet is opened as better shown in Fig. 1 all of the contents will be available and presented for use.

A partition wall 11 is formed within the 85 cabinet dividing the same up into sections and arranged within one of the sections is a plurality of partition walls 12 for dividing the same up into small sections. The section 13 is to contain the wadding, the 90 section 14 is to contain the holy water bottle 15, and a section 16 is provided in which a match case may be arranged. A purificator may be also positioned within the section 17 which is formed by placing in the section 16 95 a cabinet 19 in which is to be arranged the oil infirmorum. Pivotal secured within the cabinet 19 upon the bearings 20 is a receptacle 21 in which the oil infirmorum is to be arranged. Adapted to be placed within 100 the pocket 22 is a spoon 23. A case 24 may also be arranged within the cabinet for containing the pyres.

Secured to the bottom 1 as at 25 is a mat 26 upon which is adapted to be arranged the 105 corporal cloth 27 and this mat 26 is provided with the tabs 28 by which the outer or free end of the mat may be fastened down to the under face of the cover 6. Arranged upon the inner face of the cover 6 and at 110

each side of the corporal cloth are the plates 29 having pivotally connected thereto the arms 30. Each of the arms 30 comprises two sections which are hingedly connected 5 as at 31 and the outer section is provided with the holders 32 in which may be arranged the candles 33. The upper ends of the candles 33 are adapted to be protected by means of the tapers 34 each of which is 10 provided with the depending apertured lugs 35 and are connected to the holders 32 by means of the elastic cord 36. Also arranged within the cover 6 is a plate 37 having hingedly connected thereto as at 38 a 15 support 39 and slidably mounted within the support 39 is the base of the crucifix 40. A leaf spring 41 is mounted upon the base 37 and is adapted to engage a lug 42 carried by the sleeve 39 so that the crucifix may be 20 retained in a vertical position when opened, but when closed the base portion of the crucifix may slide within the sleeve 39 so that its base portion will project on both sides of the pivoted connection 38, thereby preventing 25 the sleeve from moving when the crucifix is folded within the cabinet and in this manner the crucifix is held in a rigid position. The holy water bottle is provided with a stopper 42 and depending from this 30 stopper is an arm having an enlarged bulb 43. Arranged within this enlarged bulb 43 is a plurality of openings whereby when the bulb is inserted within the holy water the rite will accumulate therein and by with- 35 drawing the stopper 42 from the bottle the required amount of holy water will also be carried therewith.

By providing a detachable connection between the free end of the mat 26 and the 40 cover 6 a pocket 44 is arranged under this mat whereby the ritual, slate, communion card, stole, surplice or other articles necessary for administrating the sacraments, as

indicated generally by the numeral 45, may be arranged.

Having thus fully described my invention, what I claim as new and desire to secure by Letters Patent is:

1. In a cabinet of the character described comprising a rectangular body portion, a rear wall hingedly connected to the body portion, a cover hingedly connected to said rear wall, a mat secured at one end within said body portion, means for detachably connecting said mat to said cover, foldable 55 candle supports arranged within said cover at each side of said mat, and a foldable crucifix support arranged within said cover at the end of said mat substantially as and for the purpose set forth. 60

2. In a cabinet of the character described comprising a body portion, a cover hingedly connected thereto, said body portion having a plurality of compartments arranged therein, ritual members supported upon said 65 cover, a crucifix included in said ritual members, a support hingedly mounted within said cover for receiving the base of said crucifix and means for retaining said support in a vertical position when the 70 cover is opened substantially as and for the purpose specified.

3. In a cabinet of the character described comprising a body portion, compartments arranged within said body portion, a cover 75 hingedly connected to said body portion, ritual members arranged within said cover, plates secured within said cover, a sectional arm pivotally mounted upon each of said plates and a candle holder carried by each 80 of said arms substantially as and for the purpose specified.

In witness whereof I have hereunto set my hand.

ALEXANDER EUSTACE MAGUIRE.
